(57) CLAIM

The ornamental design for a foldable travel bag, as shown and described.

DESCRIPTION

FIG. 1 is a perspective view of the foldable travel bag in a folded configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the foldable travel bag in a fully expanded configuration.

The broken lines illustrate portions of the foldable travel bag and form no part of the claimed design.

1 Claim, 8 Drawing Sheets
